UNITED STATES PATENT OFFICE

2,210,809

LIFESAVING DEVICE

Leonard C. Gray, Omak, Wash.

Application January 9, 1939, Serial No. 250,029

3 Claims.

(Cl. 9—17)

My invention relates to lifesaving devices and more particularly to that type known as swimmer's collars.

One of the principal objects of my invention is to provide a lifesaving device adapted to be connected about the neck of a user thereby insuring the holding of the user's nose and mouth above the surface of the water to preclude drowning.

Another object of my invention is to provide a device of the character described which is simple in construction, durable in use, efficient in operation and economical in manufacture.

An important object of my invention is to provide a device of the character described fashioned with a plurality of inflatable compartments whereby to maintain the swimmer's head above the surface of the water upon puncturing of one compartment.

Other objects and advantages will be apparent from the following description, appended claims and annexed drawing.

Referring to the drawing wherein like reference characters designate like parts throughout the several views:

Figure 1 is a top plan view of my invention, partly in section.

Figure 2 is a sectional view taken on the line 2—2 of Figure 1 and illustrating the invention as applied about the neck of a user.

Figure 3 is a detail sectional view taken on the line 3—3 of Figure 1 and illustrating in dotted lines the device in collapsed or deflated condition.

Figure 4 is an end elevation of my invention illustrating the ends thereof in separated condition.

Figure 5 is a detail sectional view taken on the line 5—5 of Figure 2.

Figure 6 is a detail sectional view on an enlarged scale taken on the line 6—6 of Figure 5.

My novel form of swimmer's collar comprises a tube 4 of a circular configuration when inflated and formed with end walls 5 adapted for abutting engagement with each other and with connected front and rear walls 6 and 7 respectively.

The rear wall 7 defines a centrally disposed neck opening 8. The rear wall 7 of the tube is fashioned of semi-yieldable material while the remaining walls of said tube are fashioned of resilient material, for instance rubber.

The tube is fashioned with a circumferentially extending resilient inner wall 9, the ends of which are integrally connected to the rear wall 7 in spaced relation and the intermediate portion of said wall 9 is adapted to be disposed in proximity to the outer wall 6 of the tube as clearly illus-

trated in Figures 1 and 2 of the drawing. The inner wall 9 serves to divide the tube into outer and inner air chambers 11 and 12 respectively.

Mounted in the outer wall 10, at the front end of said tube, is a pair of air pipes 13 and 14 respectively, the pipe 14 extending through the outer chamber 11 and communicating with the inner chamber 12 and the pipe 13 having communication with the outer chamber 11 as clearly illustrated in Figures 2 and 5 of the drawing. Mounted on the pipe 14, within the outer chamber 11, is a spacing sleeve 15 serving to maintain the walls 7 and 9 in spaced relation at the front of said tube. The wall 9, subjacent the pipe 14, is provided with a flapper valve 16 whereby air may be introduced into the inner chamber 12 from the outer chamber 11 and precluded by said valve from returning from said inner chamber into said outer chamber. The outer ends of the pipes 13 and 14 have secured thereon caps 13a and 14a respectively and each of said caps has mounted therein a valve member 14b having a stem 14c extending through the cap and operable to permit the exhaust or introduction of air into the respective pipe, and to the chamber connected thereto. The valve member 14b is normally maintained in seated engagement with the inner face of the cap to close an air opening 14d formed in said cap and through which the valve stem 14c projects.

Air is introduced into the inner and outer chambers through the pipe 13 and flapper valve 16 and is exhausted through the flapper valve and pipe 14 upon operation of the valve member 14b. However, air may be introduced directly into the inner chamber 12 through the pipe 14. The inner face of the rear wall 6, adjacent the end walls 5, is provided with a pair of overlapping tabs 17, one connected to each other by coacting fastener elements 18 whereby to secure said ends together. The upper frontal face of the tube, adjacent the neck opening 8 is recessed to provide a seat 20 for accommodating the chin of the user.

From the foregoing it will be apparent that when the tube is inflated and in attached condition about the neck of a user, the inner and outer chambers will serve to maintain the head of the user above the level of the water while swimming and also preclude the user from drowning. Furthermore, the outer chamber 11 serves as a guard for the inner chamber 12 and should the tube contact any object and the outer chamber be punctured thereby, the inner cham-

ber will remain inflated and thus maintain the head of the user above the water.

It is obvious that the invention is not confined to the herein described use therefor as it may be utilized for any purpose to which it is adaptable. It is therefore to be understood that the invention is not limited to the specific construction as illustrated and described, as the same is only illustrative of the principles of operation, which are capable of extended application in advance forms, and that the invention comprehends all construction within the scope of the appended claims.

What I claim is:

- 15 1. A device of the character described, comprising, a tube fashioned with end, rear, front and inner walls, and means connecting said end walls together in abutting relation whereby said rear wall defines a neck opening, said inner wall 20 coacting with said front and rear wall to define outer and inner air chambers within said tube, said outer chamber being of a crescent configuration in cross section and disposed outwardly of and about said inner chamber to protect the inner wall against puncture, said outer wall fashioned on the front face thereof with a recess 25 defining a seat for accommodating the chin of a user whereby to maintain said tube in adjusted position about the neck of said user.
- 20 2. A device of the character described, comprising, a tube fashioned with end, rear, front and inner walls, means connecting said end walls together in abutting relation whereby said rear wall defines a neck opening, said inner wall co- 25 acting with said front and rear wall to define

outer and inner air chambers within said tube, said outer chamber being of a crescent configuration in cross section and disposed outwardly of and about said inner chamber to protect the inner wall against puncture, said outer wall 5 fashioned on the front face thereof with a recess defining a seat for accommodating the chin of a user whereby to maintain said tube in adjusted position about the neck of said user, and means connected to said tube and communicating with each of said chambers whereby air may be introduced therein for inflating said tube.

3. A device of the character described, comprising, a tube fashioned with end, rear, front and inner walls, means connecting said end 15 walls together in abutting relation whereby said rear wall defines a neck opening, said inner wall coacting with said front and rear wall to define outer and inner air chambers within said tube, said outer chamber being of a crescent configura- 20 tion in cross section and disposed outwardly of and about said inner chamber to protect the inner wall against puncture, said outer wall fashioned on the front face thereof with a recess 25 defining a seat for accommodating the chin of a user whereby to maintain said tube in adjusted position about the neck of said user, means connected to said tube and communicating with each of said chambers whereby air may be introduced 30 therein for inflating said tube, and a flapper valve in said inner wall for admitting air into said inner chamber from said outer chamber and precluding discharge of air from said inner chamber into said outer chamber.
